UNITED STATES PATENT OFFICE.

JERAMIAH K. ILGES, OF TREMONT, AND GEORGE H. EARNEST, OF SPRINGFIELD, OHIO; SAID ILGES ASSIGNOR AND SAID EARNEST ASSIGNOR OF ONE-SIXTH TO IRWIN A. ILGES, OF TREMONT, OHIO.

FODDER-BINDER.

SPECIFICATION forming part of Letters Patent No. 430,385, dated June 17, 1890.

Application filed August 30, 1889. Serial No. 322,492. (No model.)

To all whom it may concern:

Be it known that we, JERAMIAH K. ILGES, of Tremont, and GEORGE H. EARNEST, of Springfield, both citizens of the United States, residing at the places named, in the county of Clark and State of Ohio, have invented certain new and useful Improvements in Husking-Tables and Fodder-Binders, of which the following is a specification.

10 Our invention relates to a husking-table and a binding device for binding fodder.

The object of our invention is to provide a simple device adapted to serve as a husking-table for husking corn from the shock, suitable means being also provided for gathering the fodder together in a bundle and binding the same after the corn has been husked therefrom.

15 Our invention consists in the various constructions and combinations of parts herein-after described, and set forth in the claims.

In the accompanying drawings, which form a part of this specification, Figure 1 is a longitudinal sectional elevation view of a device embodying our invention. Fig. 2 is a plan view of the same. Fig. 3 is a sectional view showing some of the parts in detail, hereinafter referred to. Fig. 4 is a detail view showing a modification in the cord-retaining hooks.

20 Like parts are indicated by similar letters of reference throughout the several views.

In the said drawings, *a a* represents a main frame or table, which consists, essentially, of an outer rectangular frame having center cross-bars *a' a'*. This frame is preferably constructed of wood, the parts forming the frame being as light as consistent with strength and joined together with corner angle-pieces *b*, the center cross-bars *a' a'* being joined to the main frame *a a* by channel or U-shaped pieces *b' b'*. The frame or table thus formed is supported at a suitable height by legs *d d*.

25 At or near the center of the table and extending between the cross-bars *a' a'* is a sleeve *c*, supported on a fastening-bolt *c'*, which extends through said sleeve and through the said cross-bars *a' a'*. The sleeve *c* is provided with two projecting flanges or shoulders *c' c'*, and at each end beyond said flanges with bear-

ings *c' c'*, on which bearings the binding or compressing arms *e* and *e'* are mounted, suitable washers *c' c'* being placed on said journals between said arms and the cross-bars *a' a'*. These binding or compressing arms are 55 made of sufficient length so that when in the normal position, as shown in Fig. 1, the outer ends thereof rest on the top of the frame or table *a a* on opposite sides thereof, the inner ends of said arms being extended and provided with eyes *f f'*, into which are attached connecting-links *f' f'*. These connecting-links *f' f'* are both connected at their other ends by a single connecting-eye *f' f'* to an operating-lever *g*. This operating-lever *g* is pivoted at its rear end in a hanger *g'*, which is secured to one of the cross-bars *a'* and extends downwardly beneath the frame or table *a a*. The front end of the operating-lever *g* is extended beyond the table *a a*, as shown in 70 Fig. 1, in convenient reach of the operator.

Each of the binding or compressing arms *e* and *e'* is provided with an outwardly-projecting hook *h h'*, formed integral with said arm or connected in any suitable manner thereto, 75 as shown in Figs. 1 and 4. These hooks *h h'* are cord-retaining hooks, and are adapted to hold each end of a cord *i*, with which the fodder is to be bound.

The machine as thus constructed is made 80 light and strong and is adapted to be carried by the operator to a convenient position in the field where the husking is to be done. A suitable amount of corn is taken from the shock and placed upon the table, so that the stalks 85 shall lie across the cross-bars *a' a'*. The corn is husked therefrom by the operator, who leaves the fodder spread out upon the table *a a*. After the corn is all removed the operator places his foot upon the lever *g*, which, 90 through the operation of the connecting-links *f' f'*, acting on the extended portions of the compressing-arms *e* and *e'*, forces the said arms upwardly about the fodder, gathering and compressing the same into a bundle and 95 carrying the cord *i* around said bundle in a convenient position for fastening. The hooks *h* and *h'* are preferably placed in different relative positions on the arms *e* and *e'*, the hook *h* being placed about midway in the 100

length of the arm e , while the hook h' is placed near the outer end of the arm e' . As the arms are brought up to compress the bundle, the outer ends thereof cross each other, thus bringing the ends of the cord in convenient position for tying or fastening by the operator. By having the cord-retaining hooks placed in the relative positions named the end of the cord attached to the arm farthest from the operator is brought over the top of the bundle, while the other end of the cord is left a little below the top of the bundle on the side nearest the operator.

In operation a suitable number of the cords 15 i may be prepared ready for use, so that after each bundle is compressed and tied another cord may be placed in the retaining-hooks, so as to be ready for operation. As before stated, the compressing-arms when in the normal position rest with their outer extremities on top of the table. In order to gather and compress the bundles, these arms are made of the shape shown in Fig. 1, each being formed with an 20 **S**-shaped or ogee curve, so that the outer portion k of each arm serves to gather the fodder in position within the inner portions k' of each arm, where it is compressed ready for binding, the outer curved portions k of each arm being thus adapted to gather the fodder and 25 gradually force it as the arms are raised into the inner portions k' , thus forming a shapely and compact bundle. As each bundle is secured the operator releases the lever g , and the weight and shape of the arms will cause 30 them to descend to their normal positions, as shown in Fig. 1, after which another cord is placed in the retaining-hooks and the machine is again ready for operation.

The device as thus described, it will be seen, 35 is simple in its construction and operation. It may be economically constructed, and, while

strong and durable, may be readily transported from place to place by the operator when husking corn from the shock.

Having thus described our invention, we 45 claim—

1. The combination, with a suitable frame or table, of the ogee or **S**-shaped arms concentrically pivoted near the middle of said frame or table and extending in opposite directions on each side of their pivotal center, so that the inner portions of said arms rest normally below said frame or table, with their outer extremities resting on the top on either side of said table, connecting-links extending 55 from the inner ends of said arms to a single connecting-point on the operating-lever, a pivoted connection between said lever and frame, and cord-retaining hooks on said arms, substantially as specified. 60

2. The combination, with a suitable frame or table having a straight top in a horizontal plane and provided with center cross-bars thereon, of the curved arms concentrically pivoted near the middle of said bars and extending in opposite directions on each side of their pivotal center, so that the inner portions of said arms rest normally below the upper surface of said frame or table, with the outer extremities of said arms resting on the top on 70 either side of said table, an operating-lever located under said table, and connecting-links extending from a common connecting-point to the inner ends of said arms, substantially as specified. 75

In testimony whereof we have hereunto set our hands this 24th day of August, A. D. 1889.

JERAMIAH K. ILGES.
GEORGE H. EARNEST.
